UNITED STATES PATENT OFFICE.

FRANCISCO DE LA CUESTA, MANUEL MARIA DE LA CUESTA, JUSTO PARAPAR, AND SANTIAGO FALS, OF HABANA, CUBA.

ADVERTISEMENT HOLDER.

Application filed February 26, 1927, Serial No. 171,256, and in Cuba February 12, 1927.

This invention refers to a metallic frame adaptable to the back of a seat, and which frame serves to hold an advertisement, and has for its main object, to provide an arrangement of this kind, which besides not disfiguring the outlines of the seats, but on the contrary contributing to improve same, is destined to bear removable boards or plates bearing advertisements, that is to say that the advertisement may be removed and replaced by others when desired, but while installed remains fixed and without the possibility of same being removed by anyone without using a tool, such as a screwdriver or a similar tool.

This invention may be used especially in the seats of street cars, omnibus, trains and other vehicles, but may be also used on all kinds of seats, for instance in the seats of theatres or parks.

As before said, the seat is not misshaped because the frame extends only slightly over the upper edge of the back and causes an esthetic effect, due specially to the placing of a glass or transparent plate which covers the advertisement, and because all the other parts of the frame are of metal, elaborated in accordance with the art.

More advantages and other considerations pertaining to the invention, will be deduced in the course of this specification, with the aid of the figures in the attached drawings, in which the same characters of reference designate the same parts.

Fig. 1 is a perspective view, in detail, of the upper part of the back of the seat, provided with the improvements, object of this invention.

Fig. 2 is a perspective view of the invention showing the advertisement and the glass which covers same, half placed.

Fig. 3 is a front elevation of the supporting apparatus without the advertisement.

Fig. 4 is a front elevation, broken and partially in section, of the apparatus.

Fig. 5 is a side elevation of same on an enlarged scale.

Fig. 6 is a vertical transversal section according to lines C—D of Fig. 4.

Fig. 7 is a vertical transversal section according to lines A—B of Fig. 4.

Fig. 8 is a vertical transversal section on enlarged scale according to lines E—F of Fig. 3.

Fig. 9 is a perspective view in detail of an additional part of the invention, and

Fig. 10 is a broken view of one of the holders of same.

Referring to these figures, in same is shown the invention constituted by a metallic frame, which is bent on each end, so as to adapt itself as a kind of frame over the upper part of the back of a seat A, which in the case illustrated is the seat of a street car or an omnibus. For that purpose, the main body 1, of the frame has its inner surface concaved as shown by 1' and its side surfaces recessed in its full length, except on its ends constituting a central web 1'' a transversal section of which is shown clearly in Fig. 8, having formed on each side, above and below the channeled guides 1'''.

Through the web 1'' are opened a plurality of spaced slots 3, for the purpose of lightening the weight of the frame, and at the same time to permit the setting of the screws 4 which are screwed through the bores 5 opened on the inner edge of each opening 3 and in the upper part of the back A as shown in Figures 3 and 7.

On the ends of the body 1 is formed the holders 6 and 7 of which the larger, 7, corresponds to the outer side of the seat, that is the central passage of the car or omnibus, if referring to the seat in this kind of vehicle, and for the same, presenting its upper part thinned as shown in 7' to facilitate a better hold.

The legs 8 of the frame as before said, are adapted to the sides of the back A its ends coinciding with the upper cut ends of the frame or usual metallic reinforcement 9 of the seat, and being fastened to same by means of the screws 10.

The guides 1''' on each side of the web 1', serve as a frame and holder to a long narrow plate 11 of suitable material, and on which appears the advertisement, said plate being protected by a plate of glass or transparent material 12 of the same shape, which is adjusted through the guides 1''' the lower end of said plate 12 being enclosed in a housing 8' opened in the body 1 on the border corresponding to the opening 3, adjacent to the holder 6. So that the plate 11 and the plate 12 cannot be removed from their positions, a header or cover 13, detailed in Fig. 9 is provided, which presents lateral curved re-

cesses 13' and a slot with a recess 13'' on its inner side, so as to make a closure on the end of the main body 1 which corresponds to the holder 7 for which purpose the header 13 presents on its upper and lower part the recesses 13''' which fit with recesses 14 existing in this end of the main body 1. The header 13 as detailed in Figures 1-4 and 8 is fastened by means of 10 screws 15, screwable in the bores 16 opened on the sides of the header 13 and which coincide with bores 17 opened in the corresponding end of the main body 1.

As it may be seen, the metallic frame 15 which holds the advertisement projects but slightly from the back of the seat, and does not misshape same, but on the contrary contributes to give it a better appearance, and besides, the advertisement is placed in such 20 a manner as to be removable, only by means of a tool, which serves to unscrew the screws 15, remove the header 13 and then draw out the plates 11 and 12 as shown in Figure 2, the thinness 7' of the holder 7, making the 25 realization of same easy.

It is evident that within the principles of construction explained, many modifications may be made, so that we do not limit ourselves to the previously assigned, but

we wish that the Letters Patent protect 30 that which is comprised within the scope of the following claim:

A device of the character described comprising an advertising attachment for seat backs, a frame including upper and lower parallel spaced elongated members, the upper member having its end portions turned downwardly and laterally thereto, the lower member being shaped to conform to the top edge of the seat back, and having one end portion thereof turned downwardly for a distance and spaced from the downwardly turned portion of the upper member, but having its extremity connected thereto, the frame members having inwardly directed 40 flanges on their parallel portions forming channels for embracing the sides and ends of an advertising card, and a block detachably secured between the parallel portions of said upper and lower members adjacent 45 50 said turned down portions thereof.

In testimony whereof we have signed our names to this specification.
